CLAIM

The ornamental design for an air conditioner as shown and described.

DESCRIPTION

1. Air conditioner
- 1.1 : Perspective
- 1.2 : Front
- 1.3 : Back
- 1.4 : Left
- 1.5 : Right
- 1.6 : Top
- 1.7 : Bottom
- 1.8 : Perspective view 2
- 1.9 : Front view 2
- 1.10 : Back view 2
- 1.11 : Left view 2
- 1.12 : Right view 2
- 1.13 : Top view 2
- 1.14 : Bottom view 2
- 1.15 : Exploded

The broken lines depict portions of the air conditioner that form no part of the claimed design; this design is for an air conditioner; as shown in reproductions 1.8 to 1.15, since the front upper part of this design can be opened, the user can easily clean the inside; reproductions 1.1 to 1.7 show the state in which the front upper part has been closed, and reproductions 1.8 to 1.15 show the state in which the front upper part has been opened; reproduction 1.15 is an exploded view of reproduction 1.8 in which the fan door has been separated.
